ELEVATOR CAR-BORNE MECHANISM FOR
TRANSLATING PIN-ENGAGING JAWSWestropp Armstrong, Philadelphia, Pa., assignor
to Armstrong Riding Car Operator Corp., Chi-
cago, Ill., a corporation of Illinois

Application December 9, 1949, Serial No. 132,162

15 Claims. (Cl. 187—52)

1

This invention relates to a mechanism for translating the pin-engaging jaws of a riding car operator.

In the elevator art, there are two types of mechanisms for opening the level doors in the shafts. These types are not exclusive but are here differentiated in order to assist in an understanding of the invention and the explanation thereof. These types are first—the type in which the door or doors at each landing are opened and closed by a mechanism associated with the respective level, so that there are the same number of mechanisms as there are levels; and second—the type in which there is a single mechanism carried by the elevator car which is coupled in some manner to the door or doors at each level when the car arrives thereat. So, if the mechanism is an electric motor and linkages, in the first type there are a plurality of motors stationed one or more at each level, and in the second type there is a single motor carried by the car.

The mechanism which opens and closes the door is known as an operator, and the second type alluded to above is known as a riding car operator.

This invention is limited to a riding car operator. Attention is invited to my co-pending application Serial No. 101,734, filed June 28, 1949, now Patent No. 2,578,459, for an Elevator Closure Operating Mechanism, in which I describe an elevator having a riding car operator and with which my present invention can be used. In the said co-pending application, the elevator car did not have a door or gate and hence the operator could be placed on the roof of the car at any convenient position, but in the structure shown here the car is presumed to have a gate of its own and hence the operator is arranged to permit the gate to move vertically past the entrance to the car so that there can be no parts protruding into the path of the car gate. This arrangement necessitates the motor and gear box to be placed at one side of the car, while the pin-engaging jaws and associated structure is at the opposite side of the car, being connected by appropriate linkages within the confines of the vertically movable car gate, but it is desired to point out that such an arrangement while promoting safety and desirable from that standpoint is not required from a functional standpoint. In other words, my present invention is applicable to the type of car which has no gate.

My present invention is equally applicable to installations where the doors at the respective levels are intended to open vertically or horizontally. The only structural requirements are that the door opening mechanism at each level have a pin which projects into the elevator shaft, the pin is adapted to be engaged by a part of

2

the riding car operator when the level is reached by the car, and horizontal translative movement of the said part in a plane parallel with the plane of the doors will serve to actuate the door opening mechanism through the medium of the pin.

From the above discussion it should be apparent that objects of the invention lie in the provision of an efficacious riding car operator intended to open the doors at the respective levels, and intended to accomplish the functions outlined above.

Additional objects of the invention are concerned with the constructional details of such a riding car operator.

Considering now the arrangement of the parts of the installation, from a practical standpoint there must be provision for certain variations of the positions of said parts. The operator of my invention presents a pair of vertical jaws to the respective pins as the car rides up and down the shaft. The jaws must clear the pin of every level as the car rides by and there will be a certain amount of play, and variations in the location of the pin. Therefore the jaws must be considerably further apart than the diameter of the pin, or else a pin may at one time or another miss the entrance to the space between the jaws and cause great damage to the installation. My invention therefore contemplates that the operator shall provide such wide space when the car is passing any level or is at rest alongside a level. When however the operator is set in motion at a given level, the jaws are designed to take up the unoccupied space by approaching one another until engaged with the pin. Thereafter the operator translates the jaws to open the door. The jaws remain in their engaged position while the door is being opened, while it remains open, and as it is being closed, but when the door finally has been closed by the operator, a last function of the mechanism spreads the jaws once more so that the pin is clear and the car can be safely moved up and down the shaft.

Additional objects of the invention are concerned with the provision of the jaw spreading and narrowing mechanism as well as the provision of such a mechanism which is simple, efficient, positive, extremely economical and takes up very little space.

Another object of the invention is to provide means for bracing the elevator car against the shaft walls while the operator is functioning.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, pro-

portion, size and minor details of the structure may be made without departing from the spirit or sacrificing any of the advantages of the invention.

For the purpose of facilitating an understanding of this invention, there is illustrated in the accompanying drawings a preferred embodiment thereof, from an inspection of which, when considered in connection with the following description, this invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is an elevational view of a riding car operator constructed in accordance with my invention, looking at the same from the rear of the elevator car toward the front thereof. In this view the car is at rest alongside one level with the doors at the level closed. This is also the condition which prevails as the elevator car moves from level to level.

Fig. 2 is an enlarged elevational view of the left hand end of the riding car operator, the jaws being shown in the position where same have approached one another to engage upon the pin of the door opening mechanism so that the pull rod may be actuated to translate the jaws in opening the doors.

Fig. 3 is a sectional view through the mechanism taken along the line 3-3 of Fig. 2 and in the indicated direction.

Figs. 4 and 5 are views similar to that of Fig. 2 but showing different conditions of operation of the riding car operator resulting in different positions of the component parts thereof.

Fig. 6 is a side elevational view of the right hand end of the operator showing the construction by means of which power is applied through the linkages of the riding car operator, various positions of the mechanism being shown.

Generally my new construction includes a source of rotational power in the form of an electric motor and associated gear reduction controlled from the inside of the elevator car, the pin-engaging jaws, and means connected between the motor and each of the jaws. One jaw is connected directly to a crank arm which is rotated by the motor. The second jaw is movable relative to the first but it is connected by means of a toothed coupling device to the first for certain purposes. A push rod arrangement determines the manner of connection and the push rod is actuated by the rotation of the crank on the motor.

The device operates as follows: In initial position the jaws are spread. The first movement of the crank arm takes up the slack on the right side of the pin by positive movement of the directly connected jaw. The toothed coupling device of the second jaw in initial position is inoperative and the jaw is held in its furthest position to the left against the bias of a spring by a push rod engaged by the crank arm. As the crank arm moves taking up the slack as described, the push rod is pulled to the right by a second spring, rendering the toothed coupling device operative and permitting the first spring referred to to pull the second jaw to the right until it engages the pin. Further movement of the crank arm has no effect upon the push rod, but pulls the coupled jaws to the right opening

the level doors. Reversal of the rotation of the motor, pushes the jaws to the left, closing the doors; and spreads the jaws after the doors have been closed. The directly coupled jaw is moved slightly to the right by a slight rotation of the crank arm past dead center, and during this movement, the toothed coupling device is disengaged and the push rod moves the second jaw to the left. The jaws are thus returned to their initial position.

The above explanation is a general one, and made with reference to the drawings as to the right and left designations. Obviously the reverse arrangement will operate in the identical manner.

Referring now to the details of my invention, in the drawings I have illustrated the pertinent parts of an elevator installation, in which the reference character 10 designates generally an elevator car riding in a shaft 11 defined by walls 12 and carrying upon the roof of said car a riding car operator 13 constructed in accordance with my invention. The construction of my invention enables a completely unobstructed entrance to the car 10, the bulky portions of the mechanism being disposed at opposite sides of the car. Thus for example, the left hand end of the operator mechanism is extremely thin as demonstrated by the appearance thereof in section in Fig. 3. Note also that the motor 14 and its associated mechanism is placed off to the right to permit clearance.

There is provided an elongate framework which may be of any suitable construction for guiding and confining the linkages. I have illustrated top and bottom stringers 15 and 16 extending the entire width of the elevator car 10, and having vertical cross bracing provided by spacers 17 and 18, end gusset plates 19 and 20, and possibly other spacer members such as 21 shown in Fig. 4. The stringers may be formed of channels or angles as desired. The exact details of construction of the framework are not important, providing the described functions are accomplished thereby. At its left end, a protective angle iron 22 may be secured.

The framework is secured to the car 10 and is rigid throughout its extent since the motion produced adjacent the motor 14 must accurately be transmitted to the opposite side of the car by mechanical means supported by the framework.

The motor 14 is supported by a platform 23 since same may protrude beyond the normal extent of the car. The rotation of the motor 14 serves to rotate a crank arm 24 pivotally secured at 25 to a connecting rod 26. The rod 26 in turn is secured to a cross head 27 by means of a wrist pin 28 and the cross head is confined within the framework between the stringers 15 and 16 by any suitable cross head guides which are here not shown, but which may include the flanges 29 and 30 of the stringers 15 and 16. Obviously the cross head 27 will be reciprocated or translated in a horizontal direction either right or left by rotation of the crank arm 24. I have shown an arrangement in which there is a toothed pinion 31 secured to the shaft 32 of the motor 14 and rotatable therewith, and a second pinion 33 adapted to be rotated by pinion 31 and hence enmeshed therewith. The crank arm 24 is secured to the shaft 34 of the pinion 33 and rotates therewith. This arrangement is necessary only in case it is desired to conserve space, since it is practical to secure the crank arm 24 directly to the motor shaft 32 if the speed of the

motor 14 is satisfactory and there is sufficient space. Obviously there may be necessary adjustments in the dimension and proportion of the parts.

There is a boomerang shaped lever 40 pivotally mounted at 41 on the stringer 15 and having its lower end biased to the right as shown in Fig. 6 by a coil spring 42 having one end attached to the pin 43 of the lever 40 and having its other end attached to a pin 44 on the car 10. A push rod 45 is pivotally secured at 46 intermediate the ends of the lever 40 adjacent a cam edge 47 of the lever. The nose 48 of the crank arm 24 is adapted to engage the cam edge 47 during rotation of the said crank arm 24 thereby causing the lever 40 to swing about its pivot 41, thereby reciprocating the push rod 45. The movement of the crank arm 24 which moves the nose 48 away from the cam edge 47 permits the spring 42 to pull the lever 40 to the right, i. e., swing same in a counter-clockwise direction about the pivot 41, while that movement of the arm 24 carrying the nose against the cam edge 47 swings the lever 40 in a clockwise direction against the bias of the spring 42. The counterclockwise swinging of the arm 40 is limited by a stop member 49 mounted on the car 10 and adapted to be engaged by the lower end of the lever 40. This might occur in case of overcoasting of the crank arm 24 in closing the doors (not shown) where the arm 24 might come to rest at a position shown in broken lines in Fig. 6 and designated 24-A. It will occur while the doors are being opened or closed and the crank arm 24 is above dead center and not engaged with the lever 40. A typical position of the crank arm 24 while not engaged with the lever 40 is shown in broken lines in Fig. 6 and is designated 24-B, and the dead-center position is designated 24-C.

The movements of the cross head 27 and push rod 45 are transmitted to the left hand side of the riding car operator by means of the elongate rods 50 and 51 respectively. It should be noted that the upper of these two rods namely 51, is connected to the push rod 45 by an offset connection 52 which is rigid where attached to the push rod 45 but is pivoted at 53 so that the rod 51 is capable of vertical swinging about the pivot 53. The rod 50 may be rigidly connected in any suitable manner to the cross head 27 and likewise may rigidly be connected to one of the jaws in a manner to be described.

Referring now to the left hand side of the mechanism, there are provided a pair of jaws, 60 and 61 normally spaced one from the other to provide a groove or passageway extending vertically and being free on both ends so that the pin 62 which is mounted upon the lever 63 that operates the door opening linkage may readily pass therethrough when the car 10 moves up and down the shaft 11. There are tapered inside ends at 62 and 63 to provide broad-mouthed entrances to the groove or passageway which I have designated 64. In accordance with my co-pending application, the construction of the door opening mechanism is such that the pin 62 must move in a horizontal direction and I have here shown a headed extension 65 engaged in a horizontal guideway 66 secured to the wall 67 at the front of the car 10, but this construction is not required, since the pin 62 may have a vertical component of motion while being actuated to open the doors without affecting the operation of my present device.

The jaw 61 is rigidly secured to a rectangular

plate member 69 which is arranged for horizontal sliding movement between guide members 70 and 71 attached to the stringers 15 and 16 respectively as shown in Fig. 3. The rod 50 is secured at 12a to the plate member 69, so that in effect the jaw 60 is directly connected for motion with the cross head 27.

The plate 69 has a central rectangular opening 72 best shown in Fig. 5 having a toothed insert 73 in the bottom thereof. The individual teeth 74 have their right hand edges vertical and their left hand edges slanted to the left. A member having oppositely positioned teeth will therefore engage with the insert only if moved to the left relative thereto. The opening 72 is to allow space so that the parts of the coupling device to be described may be accommodated and operated.

The rear surface of the rectangular plate member 69 has a pair of guide members 75 and 76 secured thereto having their edges rabbeted so as to permit horizontal sliding movement of a second rectangular plate member 77 to which the jaw 60 is rigidly secured. As shown in Fig. 5, the plate member 77 is biased to move to the right relative to the plate member 69 by means of a coil spring 78 which extends between the pins 79 and 80 respectively of the plate members. The front surface of the plate member 77 is provided with a projection 81 and a member 82 mounting a pin 83 upon which are commonly pivoted a pair of dogs 84 and 85. Each dog has a downwardly extending tooth 86 and 87 respectively of identical shape as the teeth 74, the teeth 86 and 87 being spaced apart a distance equal to one-half of the spacing between the respective teeth 74. This permits fine steps of engagement without sacrifice of strength of the teeth. Each of the dogs 84 and 85 has an upwardly extending arm 88 and 89 respectively lying substantially against the surface of the plate 77, there being a forwardly extending projection 90 and 91 on respective arms 88 and 89. As will be noted from Fig. 5, the rod 51 is arranged to clear the arms 88 and 89, but not the projections 90 and 91, as clearly shown in Fig. 3.

The left hand end of the rod 51 is free as shown in Figs. 4 and 5, and has a blunt nose 92 adapted to engage against the projection 81 and a slanted portion 93 adapted to ride the slanted cam edge 94 of a member 95 which is secured to the brace member 21 so as to be fixed relative to the car 10. Obviously if the rod 51 moves to the left it will ride upwardly upon the cam edge 94, lifting the teeth 86 and 87 of the dogs 84 and 85 out of engagement with the teeth 74 and then push the entire plate 77 to the left because of engagement of the nose 92 with the projection 81. This movement will push the jaw 60 to the left against the tension of the spring 78 and hold same in that position so long as the rod 51 is disposed as shown in Fig. 5.

The detailed operation of the operator will now be set forth:

The initial position of the device is illustrated in Fig. 1 and by the solid lines of Figs. 5 and 6. Under these circumstances the jaws 60 and 61 are spread apart to their greatest extent so that the pins of the respective door opening mechanisms readily clear the same and move through the passageway 64 as the elevator car 10 moves up and down in the shaft 11. Note that the nose 92 of the rod 51 is holding the left jaw 60 open, and the teeth 86 and 87 clear the teeth 74.

Presume now that the elevator car 10 has stopped at a given level at which there is a set

of doors to be opened by swinging the lever 63, to be accomplished by translating the pin 62 to the right as viewed in Fig. 5. The disposition of the pin 62 relative to the jaws 60 and 61 is not very important so long as it is somewhere between the upper and lower ends thereof in the passageway 64. Thus it will be presumed that the pin 62 is disposed in the geometric center of the passageway 64 when the car 10 is stopped at a given level. In Figs. 4 and 5 the broken outline 62-A is shown to illustrate the extent of movement of the jaws 60 and 61. The motor 14 is now energized by the elevator car attendant, causing same to rotate in such a direction as to rotate the pinion 31 in a counter-clockwise direction, thereby rotating the pinion 33 in a clockwise direction. This moves the crank arm 24 from the full line position of Fig. 6 in unison with said pinion 33. The first portion of this rotation consists of movement to the broken line position designated 24-C in said Fig. 6 which is the dead-center position for the crank arm. This movement moves the cross head 27 a small amount to the left which also carries the rod 50 to a small extent to the left, as indicated by the broken lines 50-C of Fig. 5. The plate 69 is thus moved to the left and the new position is indicated by the broken lines 69-C of Fig. 5. This preliminary movement serves to take up the slack between the pin 62 and the jaw 61, so that when the crank arm 24 has reached dead center position 24-C the jaw 61 is in position indicated by the broken lines 61-C of Fig. 5 engaged against the right side of the pin 62. During this movement of the plate member 69, other things are occurring including the initiation of dropping movement of the teeth 86 and 87 of the dogs 84 and 85 into the teeth 74 of the insert 73, but since the movement of the plate 69 relative to the plate 77 is from right to left, the teeth will not engage but will slide upon one another with their slanted sides riding relative one to the other. During the most of this sliding movement, however, teeth 86 and 87 clear teeth 74 because the dogs 84 and 85 are held up by rod 51.

While the movement of the plate member 69 and the jaw 61 is occurring, the nose 48 of the crank arm 24 is riding up the cam edge 47 of the boomerang shaped lever 40, which is permitted to be pulled to the right by the spring 42 in counter-clockwise swinging about the pivot 41. The position of the lever 40 at dead center position of the lever 24 is shown by the broken lines designated 40-C. During this movement of the lever 40, the push rod 45 is pulled to the right, carrying with it the rod 51. Referring now to Fig. 2, this action carries the rod 51 to the position shown. The nose 92 moves to the right, permitting the projection 81 to follow the same because the spring 78 now pulls the plate 77 to the right relative to the plate 69. As the bottom of the rod 51 rides the member 95, the slanted edge 93 finally drops along the cam edge 94 removing the support of the rod from under the projections 90 and 91 thereby permitting the dogs 84 and 85 to drop downwardly carrying one or the other of the teeth 86 and 87 into engagement with one of the teeth 74, in this case the tooth 87. The jaw 60, of course, being secured to the plate 77 likewise moves to the right until it is firmly engaged against the left hand side of the pin 62. This position is shown in Fig. 2.

The motor 14 continues to rotate and the crank arm 24 continues to move in a clockwise direction, as indicated by the broken lines 24-B of

Fig. 6. The right hand movement of the push rod 45 is limited because of the stop member 49 engaging the lever 40, but that is immaterial since the rod 51 no longer has any effect upon the dogs 84 and 85 or the jaw 60. The connecting rod 26, however, continues to follow the crank arm 24 and in Fig. 6 is shown in broken lines on the position 26-B corresponding to the position 24-B of the crank arm. This pulls the cross head 27 and the rod 50 to the right. Looking at Fig. 2 it will be seen that this will move the plate member 69 and the jaw 60 to the right which certainly will not apply force to the pin 62, but also, since the toothed insert 73 is carried to the right, the tooth 87 engaged with one of the teeth 74 is also pulled to the right because the movement of the plate 77 relative to the plate 69 is now to the left. This causes the tooth 87 to remain engaged, and the pulling force is transmitted through the dog 84 to the member 82, and thence through the plate 77 to the jaw 60. This of course will translate the pin to the right, causing the opening of the doors.

It is desired to point out that the actions described in connection with Figs. 2 and 5 occur simultaneously, and that the use of two figures to illustrate same is only for purposes of clarity. It appears then that as the motor 14 is started up, the jaws 60 and 61 will close upon the pin 62 at generally the same time, thereby taking up all slack in the passageway 64 before the pull is exerted against the pin 62.

Presume that the door has been opened, and is now being closed. The reverse of the processes described above occur. Two positions of return are shown in Fig. 4. As the crank arm passes dead center moving now in a counter-clockwise direction, it pushes the rod 51 to the left causing the slanted portion 93 to ride up on the cam edge 94 of the member 95, lifting the dogs 84 and 85 and disengaging whichever tooth 86 or 87 was engaged with the toothed insert 73 while the nose 92 pushes against the projection 81 moving the jaw 60 to the left. The intermediate position described is indicated by the full lines of Fig. 4, while the final position is shown in the broken lines of said Fig. 4. Again, although not shown, the simultaneous movement of the plate member 69 is being at the same time accomplished by the movement of the crank arm 24 from dead center position 24-C to its full line position shown in Fig. 6. This of course once more opens the jaw 61 to the right so that finally the initial position described in connection with Fig. 5 has been achieved.

It is often desired to brace the car 10 against the walls 12 of the shaft in order to relieve any strain to which the elevator guides (not shown) may be subjected as the doors are being opened or closed. To this end, means may be provided which function simultaneously with the jaws 60 and 61 to brace the car 10. Thus, I may provide a construction shown only in Fig. 1 which includes extensions 100 and 101 on the ends of lever 40 which move when the lever 40 swings. The lower extension 101 is connected with a pivoted rod 102 guided at 103 with a shoe 104 secured to its free end adapted to engage the right hand wall 12 of shaft 11. The extension 100 has a similar pivoted rod 105 having guide means and a shoe (not shown) adapted to engage the left hand wall of the shaft. In normal position, the shoe 104 and its mate clear the wall, but while the doors are being opened or closed the shoes press against the walls and brace the car 10. The

Spring 42 may be of considerable strength to provide the bracing, or they may be provided positive means for swinging the lever 40 in a counter-clockwise direction for this purpose.

In order to render this explanation simple and clear, there have not been shown any switches or electrical interlocks or mechanical levers for latching or other purposes which may in some manner be associated with the riding car operator. Likewise, I have not shown the car gate or the mechanism for operating the same, for the same reasons. I do not wish in any way to be limited or affected by the presence of parts and apparatus which may be associated with the construction described for the purpose of rendering same more convenient to use, or safer to the human operator and occupants, or which might be required by governmental codes. Many changes and variations can be made without departing from the basic concepts of my invention as set forth herein, and it is my intention only to be limited in accordance with the claims appended hereto.

What is claimed and desired to secure by Letters Patent of the United States is:

1. In an elevator apparatus in which a car is adapted to ride up and down a shaft having a plurality of levels with door opening mechanisms at each level and each mechanism is adapted to be actuated by a lever having a pin extending into the shaft in the path of the car, and the pin is required to be translated with a horizontal component of motion in order to move the lever; a car-born mechanism having pin-engaging jaws initially arranged in spaced vertical relationship to form a passageway permitting the pin at the various levels to move unobstructedly through the passageway as the car rides vertically in the shaft, but adapted to move one towards the other to engage the pin at any given level and thereafter move in unison transversely of the shaft in one horizontal direction to supply the horizontal component of motion to the pin to open the doors, and thereafter to move in unison in an opposite horizontal direction to supply the horizontal component of motion to the pin to close the doors, and thereafter to move away one from the other to become disengaged from the pin to permit free vertical movement of the car thereafter.

2. In an elevator apparatus in which a car is adapted to ride up and down a shaft having a plurality of levels with door opening mechanisms at each level and each mechanism is adapted to be actuated by a lever having a pin extending into the shaft in the path of the car, and the pin is required to be translated with a horizontal component of motion in order to move the lever; a car-born mechanism having pin-engaging jaws initially arranged in spaced vertical relationship to form a passageway permitting the pin at the various levels to move unobstructedly through the passageway as the car rides vertically in the shaft, but adapted to move one towards the other to engage the pin at any given level and thereafter move in unison transversely of the shaft in one horizontal direction to supply the horizontal component of motion to the pin to open the doors, and thereafter to move in unison in an opposite horizontal direction to supply the horizontal component of motion to the pin to close the doors, and thereafter to move away one from the other to become disengaged from the pin to permit free vertical movement of the car thereafter, said

mechanism including a source of rotating power, a crank arm connected to the first jaw and to the power source and having a dead center position with said first jaw engaged against the pin, and a position to one side of dead center where said first jaw is spaced from the pin, but adapted to be rotated upon the opposite side of dead center during the unison movement of the jaws, the second jaw being normally urged towards said one jaw and having a coupling device for connecting said second jaw to said first jaw, and cam means operated by said crank arm rendering the coupling device inoperative and spacing the second jaw from the pin when the crank arm is in said position to one side of dead center, but permitting said second jaw to engage said pin and render the coupling device operative when the crank arm is moved at least to dead center.

3. In an elevator apparatus in which a car is adapted to ride up and down a shaft having a plurality of levels with door opening mechanisms at each level and each mechanism is adapted to be actuated by a lever having a pin extending into the shaft in the path of the car, and the pin is required to be translated with a horizontal component of motion in order to move the lever; a car-born mechanism having pin-engaging jaws initially arranged in spaced vertical relationship to form a passageway permitting the pin at the various levels to move unobstructedly through the passageway as the car rides vertically in the shaft, but adapted to move one towards the other to engage the pin at any given level and thereafter move in unison transversely of the shaft in one horizontal direction to supply the horizontal component of motion to the pin to open the doors, and thereafter to move in unison in an opposite horizontal direction to supply the horizontal component of motion to the pin to close the doors, and thereafter to move away one from the other to become disengaged from the pin to permit free vertical movement of the car thereafter, said mechanism including a source of rotating power, a crank arm connected to the first jaw and to the power source and having a dead center position with said first jaw engaged against the pin, and a position to one side of dead center where said first jaw is spaced from the pin, but adapted to be rotated upon the opposite side of dead center during the unison movement of the jaws, the second jaw being normally urged towards said one jaw and having a coupling device for connecting said second jaw to said first jaw, and cam means operated by said crank arm rendering the coupling device inoperative and spacing the second jaw from the pin when the crank arm is in said position to one side of dead center, but permitting said second jaw to engage said pin and render the coupling device operative when the crank arm is moved at least to dead center, said cam means including a push rod biased to move in the same direction as the second jaw when moving toward said pin, an actuating lever connected with the push rod, the crank arm engaging the lever and adapted to move same against the direction of bias when rotating from said position on one side of dead center to dead center, the end of the push rod being engaged against the second jaw.

4. In an elevator apparatus in which a car is adapted to ride up and down a shaft having a plurality of levels with door opening mechanisms at each level and each mechanism is adapted to be actuated by a lever having a pin

extending into the shaft in the path of the car, and the pin is required to be translated with a horizontal component of motion in order to move the lever; a car-born mechanism having pin-engaging jaws initially arranged in spaced vertical relationship to form a passageway permitting the pin at the various levels to move unobstructed through the passageway as the car rides vertically in the shaft, but adapted to move one towards the other to engage the pin at any given level and thereafter move in unison transversely of the shaft in one horizontal direction to supply the horizontal component of motion to the pin to open the doors, and thereafter to move in unison in an opposite horizontal direction to supply the horizontal component of motion to the pin to close the doors, and thereafter to move away one from the other to become disengaged from the pin to permit free and vertical movement of the car thereafter, said mechanism including a source of rotating power, a crank arm connected to the first jaw and to the power source and having a dead center position with said first jaw engaged against the pin, and a position to one side of dead center where said first jaw is spaced from the pin, but adapted to be rotated upon the opposite side of dead center during the unison movement of the jaws, the second jaw being normally urged towards said one jaw and having a coupling device for connecting said second jaw to said first jaw, and cam means operated by said crank arm rendering the coupling device inoperative and spacing the second jaw from the pin when the crank arm is in said position to one side of dead center, but permitting said second jaw to engage said pin and render the coupling device operative when the crank arm is moved at least to dead center, said cam means including a push rod biased to move in the same direction as the second jaw when moving toward said pin, an actuating lever connected with the push rod, the crank arm engaging the lever and adapted to move same against the direction of bias when rotating from said position on one side of dead center to dead center, the end of the push rod being engaged against the second jaw, and said coupling device consisting of teeth attached to the said first jaw and dog means attached to the second jaw and adapted to engage with said teeth, and said push rod having means for raising the rod and disengaging the dog means when the second jaw is pushed away from the pin.

5. In a device of the character described including a vertical shaft in which a car is adapted to ride, said shaft having a series of levels with a door opening mechanism at each level and each mechanism having a lever and a pin on said lever protruding into the shaft in operative relationship to the car, whereby said mechanism is operable when the pin is moved parallel to the plane of the door, a riding car operator mounted on said car comprising a frame, a pair of vertically arranged movable members adapted to engage said pin when the car reaches any given level, means for moving the members horizontally and thereby supplying a horizontal component of motion to the pin to open and close the doors, and said members adapted thereafter to be disengaged from said pin and remain in a spaced apart position whereby the pin can pass therebetween during the vertical movement of the car in the shaft.

6. In a device of the character described including a vertical shaft in which a car is adapted

to ride, said shaft having a series of levels with a door opening mechanism at each level and each mechanism having a lever and a pin on said lever protruding into the shaft in operative relationship to the car, whereby said mechanism is operable when the pin is moved parallel to the plane of the door, a riding car operator mounted on said car comprising a frame, a pair of vertically arranged movable members adapted to engage said pin when the car reaches any given level, means for moving the members horizontally and thereby supplying a horizontal component of motion to the pin to open and close the doors, and said members adapted thereafter to be disengaged from said pin and remain in a spaced apart position whereby the pin can pass therebetween during the vertical movement of the car in the shaft, said means including a motor for supplying rotary power, intermediate linkages connecting said members to the motor including a crank arm connecting one of said members directly to the motor, a coupling device for connecting the second member to the said first member and cam means operated by said crank arm and associated with said coupling device whereby said members are movable toward each other when the motor is rotated.

7. In a device of the character described including a vertical shaft in which a car is adapted to ride, said shaft having a series of levels with a door opening mechanism at each level and each mechanism having a lever and a pin on said lever protruding into the shaft in operative relationship to the car, whereby said mechanism is operable when the pin is moved parallel to the plane of the door, a riding car operator mounted on said car comprising a frame, a pair of vertically arranged movable members adapted to engage said pin when the car reaches any given level, means for moving the members horizontally and thereby supplying a horizontal component of motion to the pin to open and close the doors, and said members adapted thereafter to be disengaged from said pin and remain in a spaced apart position whereby the pin can pass therebetween during the vertical movement of the car in the shaft, said means including a motor for supplying rotary power, intermediate linkages connecting said members to the motor including a crank arm connecting one of said members directly to the motor, a coupling device for connecting the second member to the said first member and cam means operated by said crank arm and associated with said coupling device whereby said members are movable toward each other when the motor is rotated, said cam means including an arcuate lever pivotally mounted on said frame, a push rod pivotally secured to said lever, the crank arm engaging the lever for pivoting same whereby the end of the push rod is engaged against the said second member.

8. In a device of the character described including a vertical shaft in which a car is adapted to ride, said shaft having a series of levels with a door opening mechanism at each level and each mechanism having a lever and a pin on said lever protruding into the shaft in operative relationship to the car, whereby said mechanism is operable when the pin is moved parallel to the plane of the door, a riding car operator mounted on said car comprising a frame, a pair of vertically arranged movable members adapted to engage said pin when the car reaches any given level, means for moving the members hori-

zontally and thereby supplying a horizontal component of motion to the pin to open and close the doors, and said members adapted thereafter to be disengaged from said pin and remain in a spaced apart position whereby the pin can pass therebetween during the vertical movement of the car in the shaft, said means including a motor for supplying rotary power, intermediate linkages connecting said members to the motor including a crank arm connecting one of said members directly to the motor, a coupling device for connecting the second member to the said first member and cam means operated by said crank arm and associated with said coupling device whereby said members are movable toward each other when the motor is rotated, said cam means including an arcuate lever pivotally mounted on said frame, a push rod pivotally secured to said lever, the crank arm engaging the lever for pivoting same whereby the end of the push rod is engaged against the said second member, said coupling device comprising a plate member secured to said first member, a rod connecting said plate member directly to said crank arm, teeth attached on said plate member and dog means attached to said second member and adapted to engage with said teeth, the said push rod having means for disengaging the dog means when the second member is pushed away from the pin.

9. In a device of the character described including a vertical shaft in which a carrier is adapted to ride up and down, said shaft having a series of levels with a door opening mechanism at each level and each mechanism having a lever and a pin on said lever projecting into said shaft in operative relationship to the car, and a pair of pin-engaging members on said car having means associated therewith for moving said members into engagement with said pin at each level and thereafter to push said members away from said pin whereby the pin can pass therebetween as the carrier rides up and down the shaft, a coupling device connecting the first pin-engaging member to the second pin-engaging member comprising a plate member rigidly connected to the said first pin-engaging member, a slidable member associated with said plate member and connected to said second pin-engaging member, teeth attached on said plate member and dog means secured to said slidable member adapted to engage with teeth whereby movement of said plate member in one direction will move the slidable member in an opposite direction thereby urging said pin-engaging members toward each other to engage the said pin and away from each other for permitting passage of said pin therebetween.

10. In a device of the character described including a vertical shaft in which a car is adapted to ride, said shaft having a plurality of levels with a door opening mechanism at each level and each mechanism having a lever and a pin extending into said shaft in operative relationship to said car and a car riding operator mounted on said car adapted to be coupled with said door opening mechanism when the car is stopped at each level, a pair of vertically arranged pin-engaging jaws movable by said operator from a point removed from said jaws, said jaws adapted to be moved into operative engagement with said pin for opening and closing the doors at any given level and said jaws adapted thereafter to

be moved apart from said pin and remain in spaced vertical relationship whereby the pin can pass therebetween during the vertical movement of the car in the shaft.

- 5 11. In a device of the character described, means for moving a pair of pin-engaging jaws one relative to the other including a crank arm directly coupled to one jaw and means for rotating said crank arm, and cam means engaged by the crank arm in its rotary motion and connected with the second jaw to cause relative motion.
- 10 12. In a device of the character described, means for moving a pair of pin-engaging jaws one relative to the other including a crank arm directly coupled to one jaw and means for rotating said crank arm, and cam means engaged by the crank arm in its rotary motion and connected with the second jaw to cause relative motion, and means for temporarily coupling the jaws together at a predetermined point.
- 15 13. In a device of the character described, means for moving a pair of pin-engaging jaws one relative to the other including a crank arm directly coupled to one jaw and means for rotating said crank arm, and cam means engaged by the crank arm in its rotary motion and connected with the second jaw to cause relative motion, and means for temporarily coupling the jaws together at a predetermined point, comprising a dog and tooth coupling device.

20 14. In a device of the character described including a vertical shaft in which a car is adapted to ride, said shaft having a series of levels with a door opening mechanism at each level and each mechanism having a lever and a pin on said lever protruding into the shaft in operative relationship to the car, whereby said mechanism is operable when the pin is moved parallel to the plane of the door, a riding car operator mounted on said car comprising a frame, a pair of vertically arranged movable members adapted to engage said pin when the car reaches any given level, means for moving the members horizontally and thereby supplying a horizontal component of motion to the pin to open and close the doors, and said members adapted thereafter to be disengaged from said pin and remain in a spaced apart position whereby the pin can pass therebetween during the vertical movement of the car in the shaft, said moving means including bracing members adapted to be moved into engagement on opposite sides of the shaft while the vertically arranged members are engaged with said pin.

25 15. In a device of the character described, means for moving a pair of pin-engaging jaws one relative to the other including a crank arm directly coupled to one jaw and means for rotating said crank arm, and cam means engaged by the crank arm in its rotary motion and connected with the second jaw to cause relative motion, and a pair of car-bracing members associated with the cam means and adapted to move in opposite direction thereby.
